(No Model.)

J. F. LANDERS.
Wire Stretcher.

No. 239,103.

Patented March 22, 1881.

Witnesses,

Charles S. Remond, Inventor,
Albert A. Barker, John F. Sanders

UNITED STATES PATENT OFFICE.

JOHN F. LANDERS, OF AUBURN, ASSIGNOR TO WASHBURN & MOEN MANUFACTURING COMPANY, OF WORCESTER, MASSACHUSETTS.

WIRE-STRETCHER.

SPECIFICATION forming part of Letters Patent No. 239,103, dated March 22, 1881.

Application filed January 15, 1881. (No model.)

To all whom it may concern:

Be it known that I, JOHN F. LANDERS, of Auburn, in the county of Worcester and Commonwealth of Massachusetts, have invented 5 certain new and useful Improvements in Fence and Telegraph Wire Stretchers; and I do hereby declare that the following is a full, clear, and exact description of the same, reference being had to the accompanying drawings, forming a part of this specification, and in which—

Figure 1 represents a top or plan view of one of my aforesaid wire-stretchers when applied to an ordinary fence-post or telegraph-pole, as 15 will be hereinafter more fully set forth. Fig. 2 represents an end view of the device, looking in the direction indicated by arrow *a*, Fig. 1, the post or pole represented in said Fig. 1 not being shown in this instance; and Figs. 3 and 20 4 represent different views of a portion of the device, which will be hereinafter more fully described, Fig. 3 representing a side view of a threaded bearing-hub, and Fig. 4 a vertical section through the same, taken on line A B of said Fig. 3.

My invention is designed to be used principally for stretching what is known as "barb fence-wire" in the operation of securing the same upon a line of posts, as hereinafter described; but it may also be used for stretching telegraph or other wires with equal facility and as good results.

It consists in a device which may be so constructed and arranged as to be easily and 35 quickly adjusted and secured, by means of a forked arm or lever, to the side of an ordinary fence-post or telegraph-pole, and then operated so as to draw the wire taut by turning an arbor which is provided with a handle and 40 threads and arranged in suitable bearings, thereby coiling a rope around the same, which is secured at one end to said arbor, and provided at its other outer end with a clamping device which gripes the end of the wire when 45 the latter is placed between the jaws of the device and drawn forward, as will be hereinafter more fully explained.

To enable those skilled in the art to which my invention belongs to make and use the same, 50 I will proceed to describe it more in detail.

In the drawings, *b* represents an ordinary

fence-post in section, and *c* a forked arm or grappling-iron, which is hinged, at *d*, to the frame-work *e* of the stretcher, and by means of which forked arm the whole device is secured to post *b* by driving the pointed end *f* of the same into the post, as represented by dotted lines in Fig. 1. The side *g* of frame *e* is in practice curved to fit the surface of an ordinary-sized fence-post; but it may be employed upon a larger or smaller post than the usual size.

The part *h* represents an arbor or shaft, which is provided with threads *i*, a handle, *k*, and with grooves *l l*, formed longitudinally on opposite sides of the smooth part *m* of shaft *h*, as represented by dotted and full lines, Figs. 1 and 2. Threads *i* are for the purpose of turning shaft *h* in or out by means of its handle *k*, by said shaft passing through a stationary threaded hub, *p*, which is also provided with threads upon its inner side, as represented in Fig. 4. The part *m* of shaft *h* is supported and slides back and forth in a hub or bearing, *o*, also formed upon frame *e*.

To the outer end of the threaded part of shaft *h*, near handle *k*, is secured one end of a rope or chain, *q*, by means of which, and a clamping device, *r*, secured to its outer end, the wire is drawn forward taut, so as to be secured in that condition to the fence-posts.

Clamping device *r* consists of an oblong part or link-piece, *s*, provided at one end with a hole, *t*, for securing the outer end of rope *q* to the same, and at the other end with a hub, *u*, which forms one jaw, and a circular cam or eccentric piece, *v*, pivoted at *w*, and provided with a handle, *x*, which forms the other jaw of the device. In securing the end of the wire in said device, the handle is first swung out so as to open the jaws, when the wire is then inserted between them and the handle *x* swung back again, as represented in Fig. 1 of the drawings, thereby gripping the wire, and as it is drawn forward the strain upon the cam part *v* causes the latter to grip the wire still tighter, and effectually prevents its drawing out as the device is drawn forward by coiling the rope *q* upon shaft *h*, as represented in Fig.

1. Shaft *h* is prevented from turning back, as 100 rope *q* is coiled upon the same, by means of a ratchet-wheel, *y*, pawls *y'* and *y''*, which are

pivoted at $e' e'$, and projections $z z$, which are formed on the inner side of ratchet-wheel y , and fit into grooves $l l$, as represented in Fig. 2. Thus by this arrangement the shaft is allowed to slide back and forth in bearing o , as well as prevented from turning back. Pawl y' , which is provided with a hook upon its outer end for catching and holding against the teeth of ratchet-wheel y , prevents the shaft from turning back when the stretcher is applied to a post upon the side represented in Fig. 1; and pawl y^2 is for preventing its turning back when it is secured upon the opposite side of the post. Therefore the stretcher may be used for producing a tension upon the wire, either to the right or left of the line of posts, with equal facility.

The operation of securing a strip of barb fence-wire to a line of fence-posts, which in practice are placed about sixteen feet apart, is as follows: The wire is first uncoiled from the spool or reel and laid along the ground by the side of the posts, and one end securely fastened to the post coming nearest to that point, after which the stretcher is then grappled or secured to a post at a suitable distance from the fastened end of the wire upon the proper side to pull said wire taut. The rope q of the stretcher is then uncoiled from shaft h (if it has not already been done) to its full extent, which in practice is about three feet, and shaft h turned up as far as possible toward hub p by means of handle k . The attendant now takes hold of the wire and draws it as taut as possible by hand, and inserts it between the jaws $u v$ of the clamping device. He then swings handle x around, so as to gripe the wire, as before described, when the stretcher and wire are then in proper position to apply the tension to the latter. The attendant now takes hold of han-

dle k and turns shaft h , so as to move it forward from post b , which operation coils the rope q about said shaft h , from where it is secured near handle k , toward the post in an even and regular manner, one coil against 45 another, as represented in Fig. 1 of the drawings, and is prevented from uncoiling by pawl y' or y^2 , as the case may be, in the manner before described. The proper tension having been applied to the wire, it is then secured, by 50 means of suitable staples, to all the intermediate posts between where it was first secured, and the stretcher, after which the stretcher is then removed by hammering upon the part c' of forked arm or grapple c , and the operation 55 hereinbefore described repeated.

From the foregoing description it will be seen that a very strong and effective stretcher is produced, and by keeping the strain upon the same close to the post to which it is secured, 60 as described, it may be made lighter than stretchers are usually made for the same purpose, and with better results.

Having described my improvements in fence and telegraph wire stretchers, what I claim 65 therein as new and of my invention, and desire to secure by Letters Patent, is—

The combination of frame part e , provided with grapping-arm c , and bearings o and p , shaft h , provided with threads i , part m , 70 grooves $l l$, and handle k , ratchet-wheel y , provided with projections $z z$, pawls $y' y^2$, rope q , and clamping device r , all constructed and combined to operate substantially as shown and described, for the purpose specified.

JOHN F. LANDERS.
